UNITED STATES PATENT OFFICE

2,369,687

STUD, RAFTER, AND JOIST BRACKET

Seymour E. Ralston, West Palm Beach, Fla., assignor to Structural Specialties, Inc., West Palm Beach, Fla., a corporation of Florida

Original application September 7, 1937, Serial No. 162,779. Divided and this application May 5, 1941, Serial No. 391,956

6 Claims. (Cl. 20—92)

My invention relates to an improvement in stud, rafter and joist brackets.

This application is a division of a joint application filed by myself and Edward A. Wadsworth, September 7, 1937, Serial No. 162,779.

The object of my invention is to provide a bracket which may be affixed to studs, rafters, joists or the like to securely hold them in proper and adjusted position on sills, ridge-pieces, plates or other parts of wooden structures.

In the accompanying drawing:

Fig. 1 is a side elevation of my bracket provided with a space therein through which a rafter or joist may pass;

Fig. 2 is an end view of the bracket shown in Fig. 1; and

Fig. 3 is a perspective view of the inside of the bracket shown in Fig. 1.

Generally, in the past, during the building of frame buildings, sills, corner-posts, studs, plates, rafters, tie-beams and the like have generally been secured together by simply nailing them by what is generally known as the commonly used method of "toe-nailing." As a result of this practice, the strength of the resultant joint is dependent entirely upon the whim and execution of the particular carpenter doing the work. By the use of my bracket for securing these elements together, it has been ascertained that building construction has not only been greatly simplified, but made infinitely more sturdy and the assembly standardized, thereby guaranteeing that all similar connections will have equal strength. It will be understood, of course, that with a standard sill or plate will be properly positioned, and above this sill or plate it is necessary to secure various other elements of frame building construction such as corner-posts, studs, rafters, or joists.

In my bracket I provide a main plate 26 which is adapted primarily for use in conjunction for securing roof rafters to a roof plate, but it may be utilized under some circumstances for the attachment of joists, or, for that matter, even studs.

The main plate 26 is provided with braces 28, which braces have, on the sides thereof remote from the main plate 26, flanges 30 which are bent at approximately 90° from the braces 28, which in turn are bent at an angle of approximately 90° from the main plate 26, thus making the flanges 30 approximately parallel to the main plate 26. A substantial part is cut out from the center of the main plate 26 and flanges 32 are bent perpendicularly to the main plate 26 to give it added

rigidity. The ends of the braces 28 are provided with ears 34 which are bent away from the brace 28 at an angle so that the ears extending from the two ends of one brace are adapted to be in approximately perpendicular planes. In this manner, an ear from each of the two braces 28 will lie approximately in one plane, while the ears from the other ends of the two braces 28 will lie in approximately parallel planes. These ears 34 are provided at the ends thereof adjoining the braces 28 with a cut-away portion 22' so that the ears may be readily adjusted to fit snugly the sides of a timber if the same should happen to be slightly larger or smaller than standard size. In order to make such an adjustment, it would be only necessary to tap the ear 34 into abutting relationship with the timber to be secured to the brace.

This bracket is particularly adapted for securing a horizontal joist or a roof rafter or the like to a sill or plate. In affixing a roof rafter to a plate, the main plate 26 is preferably first secured to the rafter by driving nails through the two center holes in the main plate 26 into the rafter heel.

After the bracket is thus affixed to the rafter, the rafter may then be positioned on the roof-plate and the rafter may be secured thereto by driving nails through the other two holes in the main plate 26 and into the roof-plate. Nails may then be driven through the holes in ears 34 into the rafter and the roof-plate. In this manner an equal distribution of nails is attained and the elements are very securely fastened together, the nails being in sheer.

This bracket may also be utilized for securing a joist to a plate or sill, the only primary difference in the mode of attaching the bracket being that in the case of a joist the bracket is first secured to the sill or plate by driving nails through the several holes in the main plate 26 of the bracket and the two lower ears 34. Then the joist will be inserted between the ears 34 extending from the ends of the brace 28 remote from the main plate 26 of the bracket, and nails will be driven through holes in the ears and into the joist.

While I have referred to certain portions of the building to which the bracket may be affixed, yet it will be understood that the bracket may be utilized in any such similar position as those described above. For example, there are many other elements of frame building construction other than the elements which are commonly known as sills, studs, roof-plates, ridgepieces,

rafters, tie-beams and the like. As an example, my bracket may be used for girders and headers where gusset bracing may be desirable or required. The use of my bracket provides a standardization of construction, and does not leave the strength of the structure dependent upon the workmanship or idiosyncrasies of an individual carpenter.

I claim:

1. In a building bracket, a plate, braces integral with said plate and in converging planes approximately perpendicular to the plane of the said plate, and ears extending outwardly from the ends of said braces and bent to be in planes at substantially right-angles to one another and to the plane of the plate, said plate having a substantially rectangular portion removed therefrom and thereby providing an open slot, said open slot being bordered on at least two sides thereof by flanges bent approximately perpendicularly to the said plate.

2. A building bracket including a plate, two edges of which converge and are bent over into planes approximately perpendicular to the plane of the plate to form braces, a rectangular portion cut from the center of said plate between the converging ends of said braces, and flanges extending along the cut edges of the plate formed by removing said rectangular portion, said flanges bent into planes substantially perpendicular to the plane of the plate.

3. In a building bracket, a plate, braces integral with said plate and in converging planes approximately perpendicular to the plane of the said plate, ears bent from the ends of said braces into planes approximately perpendicular to the plane of said plate and intercepting the planes of said braces, notches in said braces at approximately the point where said ears are bent from the braces, and flanges on said braces in a plane approximately parallel to the plane of the plate.

4. A building bracket made of a single piece of metal and including an approximately rectangular portion and a tapering portion, the said portions of the plate being in the same plane and the tapering portion flanked by an inwardly turned L-shaped flange which terminates at its ends in outwardly extending ears, said plate and ears adapted to engage different parts and surfaces of a building structure, positioned at approximately right-angles to one another whereby to brace and secure them rigidly together, and said parts of the bracket having holes therethrough to receive fastening means for securing the bracket at different points to the building structure, said fastening means being in shear in each part of the building structure thus secured.
5. A device of the character described including a plate having a substantially rectangular open slot through the major portion of the center thereof, and having two tapering portions, each of which latter portions have strengthening flanges at the edges, flanges flanking the rectangular slot and being in approximately parallel planes, and the said flanges on the tapering portions converging.
- 10 20 30 35 40 50 55 60 65 70 75 80 85 90 95
6. A device of the character described including a plate having a substantially rectangular open slot through the major portion of the center thereof, and having two tapering portions, each of which latter portions have strengthening flanges at the edges, flanges flanking the rectangular slot and being in approximately parallel planes, the said flanges on the tapering portions converging, the slot adapted to receive one of the parts to be held and braced, a rectangular part of the device adapted to be fastened to the other part of the structure, and the tapering parts of the device to be fastened to both of the parts of the structure to be held together.

SEYMOUR E. RALSTON.
